UNITED STATES PATENT OFFICE.

CLIFFORD J. WILLIAMS, OF DETROIT, MICHIGAN, ASSIGNOR TO BRIGGS MANUFACTURING COMPANY, OF DETROIT, MICHIGAN, A CORPORATION OF MICHIGAN.

DOOR LATCH.

Application filed February 16, 1925. Serial No. 9,685.

This invention relates generally to latches designed particularly for use with vehicle doors and consists of certain novel features of construction, combinations and arrangements of parts as will be more fully described and particularly pointed out in the appended claims.

In the accompanying drawings;

Figure 1 is a horizontal sectional view 10 through a vehicle door with a latch embodying my invention attached thereto.

Figure 2 is a perspective view of the latch.

Figure 3 is another perspective view of the latch.

Figure 4 is a side elevation of the latch 15 with the outside cover plate removed.

Figure 5 is a side elevation of the latch with the inside cover plate removed.

Referring now to the drawings in which 20 like characters of reference designate corresponding parts throughout the several views, the numeral 1 designates a door, preferably of a vehicle body, having a pillar 2 provided at its inner edge with a channel-shaped portion 3 which constitutes a run-way for a vertically movable glass panel 4.

In order that a latch may be mounted and operated upon the pillar 2 without interfering with the vertical movement of the glass 25 panel 4, I preferably provide a case plate 5 that is preferably U-shape in cross section and that preferably straddles the channel-shaped guide-way 3. As shown, the inner section 6 of the case plate preferably supports a swingingly mounted latch bolt 7 and the inside 30 operating means therefor, while the outer section 8 preferably supports the outside operating means for the bolts.

In detail, the bolt 7 is preferably stamped 35 from sheet metal and is provided with an up-standing shank portion 9 and a forwardly extending head 10. As shown, the shank 9 is preferably provided at its lower end with a hub 11 that is journaled in aligned openings 40 in the inner case plate section 6 and cover plate 12 secured thereto, while the head 10 is preferably beveled at its outer end and is adapted to engage a suitable keeper 13 upon a door jamb of the vehicle body.

45 In order that the bolt 7 may be retracted from either the outside or the inside of the door, the shank 9 is preferably provided at diametrically opposite points of the hub 11 with forwardly and rearwardly extending

arms 14 and 15 respectively which are adapted 55 to be actuated by a roll back 16 upon the outer section 8 of the case plate, and a lever 17 upon the inner section 6 of the case plate. As shown, the roll back 16 has a hub 18 journaled in aligned openings in the outer case 60 plate section 8 and cover plate 19 secured thereto and is provided at its forward edge with a lateral extension 20 that extends across the transversely extending portion 21 of the case plate, and is normally engaged by a 65 corresponding lateral extension 22 of the arm 14. Any suitable means may be engaged with the square opening 23 in the hub 18 for rocking the roll-back 16 so that the lateral extension 20 thereof will raise the lateral extension 22 of the arm 14 and cause the latter to retract the bolt. The lever 17 normally 70 engages suitable spaced lugs 24 and 25 respectively on the forward edge of the arm 15 and is preferably provided at its lower end 75 with a flat rounded head 26 that is pivotally mounted on the inner section 6 of the case plate between the shank 9 and rearwardly extending arm 15. Any suitable means such as the helical spring 27 engaging the rearwardly extending arm 15 may be employed for normally holding the bolt head 10 in projected position and also for holding the lateral extension 22 of the arm 14 in operative position 80 with respect to the lateral extension 20 85 of the roll-back 16. Thus, with this construction, the roll-back 16 may be actuated from the outside of the door to retract the bolt without affecting the lever 17 and the latter may in turn be swung to the rear against the 90 arm 15 without affecting the roll-back. In order that the outside operating means may be rendered inoperative from the outside of the vehicle, I preferably provide a dog 28 that is pivoted on the outer section 8 of the case 95 plate and is adapted to swing behind a lug 29 on the roll back 16 to prevent the upward swinging movement of the extension 20. This dog 28 is normally held out of the path of the lug 29 against the struck out lug 30 100 on the case plate section 8 by means of a coil spring 31 anchored on the case plate section 8 and may be moved by any suitable means into operative dogging position. As shown, the dog 28 is preferably actuated by a suitable 105 cam 32 rigidly secured to the rotatable cylinder 33 of an auxiliary lock 34 which is preferably anchored in a tubular housing 35

projecting laterally from the cover plate 8 and any suitable means such as the screw 36 threadedly engaging the laterally attaching flange 39 of the case plate, may be employed 5 for holding the lock 34 within the housing 35.

In order that the outside operating means may be rendered inoperative from the inside of the door, I preferably provide a dog 40 that is adapted to be moved by the inside operating lever 17 into operative dogging position behind a shoulder 41 of the bolt shank 9 for preventing the bolt from being retracted from the outside of the door. As shown, this dog 40 is preferably pivoted on a pin 42 10 anchored upon the inner section 6 of the case plate and is normally held out of the path of the bolt shank by means of a suitable spring 43 secured to the case plate section 6. Moreover the forwardly extending portion 10 of 15 the bolt is provided at its upper edge with a recess portion 44 to receive the dog 40 when the bolt is retracted. With this construction, the dog 40 may be detachably held in operative dogging position by means of the lever 20 17. As shown, a suitable leaf spring 45 is anchored upon the inner face of the cover plate 12 and is provided at one end with an inwardly extending rib 46 that is engageable with a suitable depression 47 in the outer face 25 of the lever 17 when the latter is in its forward position. When the dog 40 is in operative position behind the shoulder 41 and the lever 17 is held by the spring 45 in its forward position, the lever may be readily moved 30 to the rear from the inside of the vehicle to release the dog 40 and retract the bolt. This may be accomplished by moving the lever against the arm 15 so that the rib 46 will become disengaged from the depression 47 35 whereupon the spring 43 will automatically move the dog 40 upwardly out of the path of the shoulder 41. The roll-back 16 may then be operated from the outside of the door if desired for retracting the bolt.

To prevent the lever 17 from rattling, I 40 preferably provide a suitable spring 48 that is anchored upon the inner section 6 of the case plate and consequently holds the lever 17 against the spring-pressed dog 40 and rib 46 of the leaf spring 45. Thus, the spring 43 as well as the spring 45 cooperates with the spring 48 for normally holding the lever 17 45 against rattling.

From the foregoing description, it will be 50 readily apparent that a latch of this type may be mounted upon a door pillar having a very small cross section, consequently the vision of the occupants of the vehicle is materially increased. Moreover, the arrangement is such that the bolt 10 may be retracted from the outside of the door without interrupting the vertical movement of the glass panel 4. It will also be apparent that the outside operating means may be operated independently of the inside operating means for 55

retracting the bolt. It will also be noted that the inner cover plate 12 cooperates with the inner section 6 of the case plate for holding the lever 17 in proper position between the shank 9 and arm 15. Moreover, a lug 50 is 60 provided upon the roll-back 16 for engagement with a struck out lug 51 on the outer section 8 of the case plate for limiting the downward swinging movement of the roll-back 16. Inasmuch as the spring 27 normally 65 urges the bolt 10 forward, it will be readily apparent that the forward swinging movement of the bolt is limited by the engagement of the lateral extension 22 with the lateral extension 21 of the roll-back 16. 70

While it is believed that from the foregoing description the natures and advantages of my invention will be readily apparent, I desire to have it understood that I do not limit myself to what is herein shown and described and that such changes may be resorted to when desired as fall within the scope of what is claimed. 80

What I claim as my invention is:

1. In a latch, the combination with a case 90 plate, of a normally projected bolt having a shank pivoted thereon, means for retracting the bolt including a lever pivotally engaging the shank, and means for rendering the retracting means inoperative including a 95 dog in the path of the lever engageable with a shoulder of the shank.

2. In a latch, the combination with a case 100 plate, a latch bolt carried thereby, means operable from one side of the case plate for retracting the bolt, means including a pivotally mounted lever operable from the opposite side of the case plate for retracting the bolt, a dog in the path of the lever adapted to be moved by the latter against a 105 shoulder of the bolt for preventing retraction thereof by the first mentioned means, yieldable means normally holding said dog inoperative, and yieldable means cooperating with the yieldable means aforesaid for 110 holding said lever against rattling.

3. In a latch, the combination with a case 115 plate, of a bolt having a shank projecting at an angle therefrom, a pivot member for said shank, arms projecting from said shank at diametrically opposite sides of the pivot, and means pivoted on said case plate engageable with one of said arms for actuating said bolt.

4. The combination with a door having a 120 run-way for a vertically movable glass panel, of a latch having a case plate secured to the door, a latch bolt pivotally mounted upon the case plate upon the inner side of the door, and means straddling the run-way for operating the bolt from the outside of the door.

5. The combination with a door having a 125 run-way for a vertically movable glass panel, of a latch having a case plate strad- 130

dling the run-way, a bolt having a shank substantially parallel to and pivotally mounted upon the inner section of the case plate, an arm projecting laterally from said shank and extending across the forward edge of said case plate, and means carried by the outer section of said case plate having a portion disposed in overlapping relation to and engageable with said arm for retracting 10 said bolt.

6. The combination with a door having a run-way for a vertically movable glass panel, of a latch having a case plate straddling the run-way, a bolt having a shank pivoted upon 15 the inner section of the case plate, an arm projecting from said shank having a lateral extension in advance of the case plate, and a roll-back mounted upon the outer section of the case plate having a lateral extension engageable with the extension aforesaid for 20 retracting the bolt.

7. The combination with a door having a run-way for a vertically movable glass panel, of a latch having a case plate secured to the 25 door, a latch bolt having a shank pivotally connected to the case plate upon the inner side of the door, an arm projecting from said shank, and means movable longitudinally of the door and exteriorly of the run-way for actuating said arm to retract the bolt.

8. The combination with a door having a run-way for a vertically movable glass panel, of a latch having a case plate straddling the 35 run-way, a bolt having a shank mounted upon the case plate, an arm projecting from said shank, and means disposed in overlapping relation to said arm and movable longitudinally of the free edge of the door for 40 actuating said arm to retract the bolt.

9. In a latch, the combination with a case plate, of a latch bolt having a shank pivoted thereon, an arm projecting from said shank having a lateral extension in advance of the 45 case plate, and a member mounted upon the outer section of the case plate having a portion disposed in overlapping relation to and engageable with the extension aforesaid for retracting the bolt.

50 10. The combination with a door having a run-way for a vertically movable glass panel, of a latch having a case plate secured to the door, a latch bolt having a shank pivotally mounted upon the case plate, means 55 operable from one side of the case plate for retracting the bolt, means including a pivotally mounted lever operable from the opposite side of the case plate for retracting the bolt, and a dog in the path of the lever adapted to be moved by the latter against a shoulder of the bolt for preventing retracting thereof by the first mentioned means.

11. In a latch, the combination with a case 60 plate, of a latch bolt provided with a shank pivoted on said case plate having radially

extending arms, one of said arms having a lateral projection extending transversely of and in advance of the case plate, and means engageable with said projection for actuating said bolt.

12. In a latch, the combination with a case plate, of a latch bolt having a shank pivoted on said case plate, arms extending from said shank, one of said arms having a lateral projection movable exteriorly of the case plate, 70 yieldable means engaging another of said arms and normally holding the bolt in extended position, means engageable with the first mentioned arm for actuating the bolt against the tension of said yieldable means, and 75 means engageable with the last mentioned arm and operable independently of the actuating means aforesaid for retracting said bolt against the tension of said yieldable means.

13. In a latch, the combination with a case 80 plate, of a swingingly mounted latch bolt mounted on said case plate, actuating means for said bolt including a part journaled in a portion of the bolt and having an edge engageable with another part of said bolt.

14. In a latch, the combination with a case plate, of a swingingly mounted latch bolt having a shank pivoted on said case plate, arms extending radially from said shank, and actuating means for the bolt including a lever 95 journaled in a portion of said bolt between one of the arms and the bolt shank.

15. In a latch, the combination with a case plate, of a stamped sheet metal bolt having a shank pivoted on one side of said case plate, 100 an arm projecting from said shank having a lateral projection extending transversely of and exteriorly of the case plate, and means operable from the opposite side of said case plate and engageable with the lateral projection aforesaid for actuating the bolt.

16. In a latch, the combination with a case plate, of a latch bolt having a substantially flat shank pivoted on one side of said case plate and provided at substantially diametrically opposite sides of its pivot with forwardly and rearwardly extending arms, and actuating means for said bolt including means extending exteriorly of and transversely of said case plate and engageable with said 110 forwardly extending arm, and a member normally in a plane substantially parallel to the plate and engageable with the rearwardly extending arm.

17. In a latch, the combination with a case 115 plate, of a latch bolt having a shank pivoted on one side of said plate and provided with a lateral projection located exteriorly of and extending transversely of said case plate, actuating means for said bolt including a member upon the opposite side of the case plate having a lateral projection engageable with the lateral projection aforesaid, and 120 yieldable means engaging a portion of said shank and normally holding said bolt in pro- 125

jected position and retaining the lateral projection of said bolt in operative engagement with the lateral projection of said member.

18. In a latch, the combination with a case plate, of a latch bolt pivoted upon one side thereof and having two projections, and actuating means for the bolt including means extending transversely of the case plate and engageable with one of said projections, and means substantially parallel to the case plate and pivoted in the bolt for engagement with the other of said projections, the connection between the last mentioned means and bolt being such that said bolt may be actuated by either of said means without effecting the other.

19. In a latch, the combination with a case plate, of a latch bolt pivoted upon one side thereof and having two projections, and actuating means for the bolt including means extending transversely of the case plate and engageable with one of said projections, and means substantially parallel to the case plate having a substantially flat rounded head pivoted in the bolt and having an upstanding portion engageable with the other of said projections.

20. In a latch, the combination with a case plate, of a latch bolt having a substantially flat shank pivoted upon one side of said case plate and having an upstanding projection in rear of and above its pivot, yieldable means engaging said projection for maintaining said bolt in a predetermined position and actuating means for the bolt including a part pivoted in the shank of said bolt and engageable with said upstanding projection.

21. In a latch, the combination with a case plate having a portion attachable to one side of a door and having a lateral portion for extending across the vertical free edge of a door, a latch bolt pivotally mounted on one side of the first mentioned portion of said case plate and having two projections, and actuating means for the bolt including means located exteriorly of and extending across the lateral portion of said case plate operatively connected to one of said projections, and means upon the first mentioned portion of said case plate operatively connected to the other of said projections.

22. In a latch, the combination with a case plate, of two pivotally mounted elements upon opposite sides of the case plate and having portions disposed in overlapping relation and at substantially right angles to said case plate, one of said elements having a projection constituting a latch bolt.

23. In a latch the combination with a case

plate, of two pivotally mounted elements 60 upon opposite sides of the case plate, and having portions disposed in overlapping relation at one edge of said case plate, one of said elements having a forward projection constituting a latch bolt and having an upstanding projection, and actuating means for the bolt including a member journaled in one of said elements and having a portion engageable with said upstanding projection.

24. In a latch, the combination with a case plate, of a member formed of flat metal stock and having a portion constituting a shank pivoted on said case plate, and two other portions projecting from the portion aforesaid and constituting a latch bolt and an arm respectively, and means extending around an edge of said case plate and engaging said arm for actuating said bolt.

25. In a latch, the combination with a case plate, of a member formed of flat metal stock and having a portion constituting a shank pivoted at one end on said case plate, and two other substantially parallel portions projecting from the portion aforesaid at opposite ends thereof and constituting a latch bolt and an arm respectively, and means extending around an edge of the case plate and engaging said arm for actuating the bolt.

26. In a latch, the combination with a case plate, of a member formed of flat metal stock and having a portion constituting a shank pivoted on the case plate and provided with an arcuate recess, a projection at one edge of said recess, and a portion projecting from the portion aforesaid and constituting a latch bolt, and actuating means for said bolt including an element having an end journaled in the recess aforesaid in said shank and slideable over one side of said case plate for engagement with said projection.

27. In a latch, a case plate, a lever movable over but entirely free from said case plate and constituting a bolt retracting member and having a rounded end portion constituting the pivot point of said lever, and a bolt carried by the case plate and having a shank provided with a recess receiving and constituting a pivotal bearing for the said rounded portion.

28. In a latch for doors and the like, a case plate, a latch bolt carried thereby, and retracting means for the bolt including a lever movable over but entirely free from said case plate and having a part journaled in and carried by a portion of said latch bolt.

In testimony whereof I affix my signature.

CLIFFORD J. WILLIAMS.
